UNITED STATES PATENT OFFICE.

WALDERMA C. SCHAUFLER, OF MOHAWK, NEW YORK.

GARMENT.

1,271,086.

Specification of Letters Patent.

Patented July 2, 1918.

Application filed November 16, 1916. Serial No. 131,621.

To all whom it may concern:

Be it known that I, WALDERMA C. SCHAUFLER, a citizen of the United States, residing at Mohawk, in the county of Herkimer and State of New York, have invented certain new and useful Improvements in Garments, of which the following is a full, clear, and exact description, such as will enable others skilled in the art to which it appertains to make and use the same.

This invention relates to undergarments, and with respect to its more specific features, it is especially applicable to knitted union suits.

One of the objects of this invention is to enable a garment to be constructed with the body and leg portions of different pieces of fabric without such weakness at the seam as has heretofore been present.

Another object is to produce a more practical garment in which the body and limb portions are of different material, whereby the one may be warmer and softer than the other to compensate for different degrees of activity and different sensitiveness of the skin of different portions of the body.

Another object is to enable a garment of the character described to be joined together in such a way as to utilize the seam to the greatest advantage whereby a firmer joining can be obtained without the presence of a seam so heavy and thick or so disposed as to be uncomfortable.

Other objects will be in part obvious and in part pointed out hereinafter.

The invention accordingly consists in the features of construction, combinations of elements and arrangement of parts which will be exemplified in the construction herein-after set forth, and the scope of the application of which will be indicated in the following claims.

In the construction of undergarments it is desirable that the body portion shall be of warmer material than the leg portions, and that it shall present a softer touch to the skin because of the greater sensitiveness of the skin of the body than of that of the legs, and because greater warmth of material is desirable. It is advantageous, therefore, that an undergarment shall be constructed with the leg portions made of separate pieces of material from the body portion. A serious difficulty in the construction of garments in which the legs are of separate pieces from the body lies in the fact

that the strains imposed upon the fabric by movements of the wearer if borne by the seam would tend to tear out the seam, unless the seam be made so heavy or be so disposed as to be uncomfortable.

One of the chief strains to which the seam joining the leg portion to the body portion of an undergarment is exposed is that due to the spreading of the legs when the wearer is in a sitting posture. This strain runs diagonally outward toward the knee from the crotch to the outer side of the leg, and one of the aspects of this invention comprises the construction of a seam in the direction of this strain.

While the broader aspects of this invention manifest themselves with whatever material the garment may be made, yet the invention has particular advantages when used in connection with a garment of a knitted material; and furthermore, while this invention is applicable to all garments in which it is desirable to make a leg portion separate from the body portion, it has especial applicability to union suits. The invention is therefore illustrated in its preferred embodiment as a knitted union suit.

In the drawings forming part of this specification, and wherein similar characters refer to similar parts throughout the several views:

Figure 1 is a front view of the garment; Fig. 2 is a view showing the garment as it would be on a wearer, with legs spread so as to subject the garment to strain; and

Figs. 3 and 4 are enlarged views of the crotch construction from the front and rear, respectively.

In the form illustrated, the garment comprises a body portion 1, leg portions 2, and arm portions 3. The courses, that is, the general direction of the thread, in both the body portion and leg portions are most conveniently made transverse to the longitudinal direction of the garment, as illustrated in Fig. 2. The leg portions 2 and the body portion 1 are each, at the point where they are to be joined, cut in a complementary manner bias to the material, that is, diagonally to the courses, from a point substantially opposite the crotch downwardly to the outer side of the leg in the direction of the strain which has been mentioned. These parts are joined together by a seam. In so far as the certain aspects of the invention are concerned, it is immaterial what the

form of seam may be, but it is preferably made a longitudinally elastic seam, especially if the garment be made of knitted material, in order that the seam may stretch with the material.

A convenient method of constructing the body portion when it is made of knitted material is to form a tubular portion of the same diameter throughout for the full length 10 of the body portion. This may then be appropriately cut for the provision of a seat portion comprising under portion 10 and flap 11, and to provide the usual front opening closed by a buttoning strip 5 and buttons 4. By constructing the body portion of the garment in this manner, and of a separate piece from the leg portions, a considerable saving of material is experienced over garments which require to be knitted the 20 full length, and then cut to form the leg portions, as by the latter construction considerable material is cut away and discarded.

By constructing the body portion and leg portions separate, furthermore, it is possible to utilize a different material of different texture for each of these parts, and obviously, so far as the main features of the invention are concerned, it is possible to use any material for either. To provide a 30 soft inner surface for the body portion because of the sensitiveness of the skin of the body, it is preferred to make the body portion of especially surfaced material. This may be done by embodying on the inner surface 35 of the body portion a loosely spun yarn thereby providing a soft downy surface. The leg portions, on the other hand, because of the less sensitive character of the skin of the leg, may be made of an unsurfaced 40 material which may be advantageously of coarser knit than the body portion.

The seat portion of the garment comprising under portion 10 and flap portion 11 may advantageously have the coarses running horizontally, producing wales, that is, the small ribs produced at right angles to the courses, running longitudinally of the garment. The body portion 1 and leg portions 2, at the front, may be cut away in a 50 more or less elliptical manner, as illustrated at 7, and the lower ends of the under portion 10, and flap portion 11 may be brought around in under between the legs, with the wales substantially radial to the ellipse, and 55 attached to the body portion at the front by a seam which is preferably an elastic one. Many of the features of this invention are more strongly manifested when used in connection with the garment in which the rear 60 opening and the front opening are not continuous. With a garment of this description the spreading of the legs produces still added strain upon the material, and thereby causes this invention to have special advantages. In the form illustrated, the garment 65

is shown with the lower end of the front opening, and the forward end of the rear opening closed, as at 6. Obviously, however, in its broader aspects the invention is applicable to a garment of any other description.

By means of the invention, of which this is one embodiment, one is enabled to accomplish the advantages set forth in this specification, as well as other advantages which 75 will be manifest.

As many changes could be made in the above construction and many apparently widely different embodiments of this invention could be made without departing from 80 the scope thereof, it is intended that all matter contained in the above description or shown in the accompanying drawings shall be interpreted as illustrative and not in a 85 limiting sense.

It is also to be understood that the language used in the following claims is intended to cover all of the generic and specific features of the invention herein described and all statements of the scope of the invention which, as a matter of language, might be said to fall therebetween.

Having described my invention, what I claim as new and desire to secure by Letters Patent is:

1. A knitted undergarment comprising a body portion, a leg portion and a crotch portion, said body portion and said leg portion having the courses running horizontally, said crotch portion being joined to said body portion along a seam forming substantially an ellipse to which the wales of the crotch are approximately radial, and said body portion and said leg portion being joined by an elastic seam bias to the fabric, running diagonally downward from the crotch portion.

2. An undergarment of knitted material comprising a body portion and a crotch portion, said crotch portion being joined to 110 said body portion by an elastic seam to form substantially an ellipse to which the wales of the crotch portion are approximately radial.

3. An undergarment of knitted material comprising a body portion and a leg portion, the body portion being joined to the leg portion by a seam running from a point directly opposite the crotch portion downwardly to the outer side of the leg.

4. In a knitted undergarment comprising a body portion and a leg portion each having courses substantially horizontal, the body portion being joined to the leg by a seam running from a point directly opposite the crotch downwardly to the outer side of the leg.

5. In an undergarment, a body portion and a leg portion joined by a seam running from a point adjacent the crotch down-

wardly to a point on the outer side of the leg between the knee and the hip.

6. A garment of the character described comprising, in combination, a body portion and a leg portion of different texture and a crotch portion seamed to the body portion and the leg portion, said body portion and said leg portion being joined by a seam running from the crotch portion to the outer

side of the leg portion and intersecting the 10 seam joining the crotch portion to the body and leg portions.

In testimony whereof I affix my signature, in the presence of two witnesses.

WALDERMA C. SCHAUFLER.
